UNITED STATES PATENT OFFICE

THEOPHILUS BROWN, OF WORCESTER, MASSACHUSETTS, ASSIGNOR TO RICHARDSON MANUFACTURING COMPANY, OF WORCESTER, MASSACHUSETTS, A CORPORATION OF MASSACHUSETTS.

MANURE-SPREADER.

1,126,698.

Specification of Letters Patent.

Patented Feb. 2, 1915.

Application filed January 24, 1910. Serial No. 539,631.

To all whom it may concern:

Be it known that I, THEOPHILUS BROWN, a citizen of the United States, residing at Worcester, in the county of Worcester and

5 Commonwealth of Massachusetts, have invented a new and useful Improvement in Manure-Spreaders, of which the following is a specification, accompanied by drawings, forming a part of the same, in which—

10 Figure 1 is a side view of a manure spreader embodying my improvement. Fig. 2 is a side elevation shown in sectional view. Fig. 3 represents an embodiment of my invention in a modified form. Fig. 4 is a detailed view of my improved apparatus in a different position.

Similar reference characters refer to similar parts in the different figures.

My present invention relates to certain improvements in manure spreaders of the common and well known type which comprise a body having a movable bottom by which the manure is carried rearwardly against the teeth of a revolving beater journaled at the 20 rear and open end of the body, said movable bottom and revolving beater being operatively connected with the rear supporting wheels of the spreader, as now commonly practised, or in any other suitable manner.

The object of my present invention is to enable the body used to be of greater depth than the vertical height of the revolving beater, by the employment of higher sides, 35 whereby an equivalent load may be carried by the use of a shorter body than that commonly employed in manure spreaders of this class.

Manure spreaders employing a rotating beater journaled in horizontal bearings distribute the load by a shredding or slicing operation of the teeth of the revolving beater against the rear end of the load as the latter is gradually moved rearwardly by the movable bottom. For the efficient operation of a beater of this class the vertical depth of the load as presented to the beater should not exceed the diameter of the beater. The vertical height of the sides of the 50 spreader body have therefore been limited, requiring an extension in the length of the body to provide increased room for the load.

As the beater necessarily revolves at a high speed it is impracticable to materially increase the diameter of the beater beyond that now in common use.

It is the object of my invention to provide means whereby the sides of the spreader body may be made considerably higher and the length of the body consequently shorter without increasing the diameter of the beater. This object is accomplished according to my present improvement by applying to the spreader and at the rear end of the body means operating upon that portion of the load which lies above the plane of the beater to move it forward and prevent its flowing over the top of the beater. To this end I employ mechanism of any suitable construction by which the upper end of the load may be forked, raked, or moved forward, as it approaches the vertical plane of the beater, thereby preventing the upper portion of the load which extends above the beater from being carried horizontally rearward over the top of the beater.

In the accompanying Drawings I have shown two embodiments of my invention, the mechanisms for accomplishing the above purpose.

Referring to the accompanying drawings 1 denotes the vertical sides of the spreader body, 2 an endless apron forming the movable bottom and carried at opposite ends of 25 the body upon sprocket wheels 3, A, revolved in the usual manner in machines of this class to move the upper section of the movable bottom rearwardly during the operation of spreading in the direction of the arrow 4, Fig. 2, thereby carrying the load against the teeth of a revolving beater 5, driven in the usual manner from the rear supporting wheels in the direction of the arrow 6. As the load is moved rearwardly by the teeth 7 of the beater rear end of the vertical rear end of the load gradually moves rearwardly upon the ground.

According to my present invention I am able to make the sides 1 of the body nearly double the height of the diameter of the beater, thereby enabling the same load of manure to be carried in a body considerably reduced in length. In order to prevent that portion of

the load which lies above the plane of the revolving beater from moving rearwardly over the top of the beater, I apply to the body a mechanism for moving the rear and upper portion of the load forward in order to keep the space directly above the beater entirely clear. The mechanism employed by me for that purpose, as represented in Figs. 1, 2, and 4, consists of a crank shaft 8 journalized in bearings mounted upon the top of the sides and provided with a sprocket wheel 9 driven by a smaller sprocket wheel 10 on the shaft of the beater 5. Extending transversely across the body but within the sides 1, 1, is a plate 11 to one side of which are attached bearings 12 which inclose cranks 13 on the crank shaft 8. To each end of the plate 11 I attach an arm 14 pivotally connected by a link 15 with a fixed bracket 16 attached to the rear end of the body. As the crank shaft 8 is rotated, a circular movement, concentric with the crank shaft, will be imparted to the plate 11, and by the pivotal connection of the arm 14 with the fixed brackets 16 through the link 15 a slight rocking movement will be imparted to the plate 11 on the crank 13 as the plate is carried in a circular path around the crank shaft, to which rotary motion is imparted in the direction of the arrow 17.

One position of the plate 11 is shown in Figs. 1 and 2, but when the crank shaft has made one half a revolution from the position shown in Figs. 1 and 2, the crank shaft 35 and connected plate will assume the position shown in Fig. 4, in which position the plate 11 is being moved downwardly. The lower edge of the plate 11 is provided with a series of teeth 18 which are carried into engagement with any manure at the top of the lower edge which may have been moved rearwardly by the movement of the bottom 2, and the manure so engaged by the continued rotation of the crank shaft will be thrown forward as the plate 11 and teeth 18 assume the position shown in Figs. 1 and 2. The continued rotation of the crank shaft 8 will therefore result in a continued movement of the top of the load forward as it approaches the beater.

During the rearward movement of the movable bottom 2 any portion of the top of the load which may be moved into the area between the top of the sides 1, 1, and the curved broken line 19 will be engaged by the teeth 18 and by the quick forward movement of the apparatus thrown into a forward position, while the rotary motion of the beater in the direction of the arrow 6 50 will act by its teeth 7 to shred and tear away the lower portion of the load on the curved line 20. In lieu of the mechanism shown in Figs. 1 and 2 for throwing forward the top portion of the load a rotating toothed roll 21 may be employed driven di-

rectly from the axle of the beater 5. The toothed roll 21 rotates in the direction of the arrow 22 and serves by its teeth 23 to move the top of the load toward the forward end of the body. When a toothed roll 21 is employed, as shown in Fig. 3, I place between the sides 1, 1, a slotted plate or a rake having teeth 24 between which the teeth 23 of the beater pass, said rake teeth 24 being placed eccentrically to the rotation of the teeth, so that as the teeth 23 pass upward the rake 24 will exert a stripping effect upon the teeth 23, thereby clearing them of any straw or manure which would otherwise be carried over the top of 80 the toothed roll 21.

I claim,

1. The combination with the body of a manure spreader, a movable bottom and a rotatable beater of less diameter than the height of said body, of a plate extending across said body having teeth, said plate pivotally connected with the top of the sides of said body, and means operative during the rotation of the beater for imparting a forward circular movement to said plate.
2. The combination with the body of a manure spreader, a movable bottom and a beater of less diameter than the height of said body, of a plate extending across said body having teeth, a crank shaft journalized on the top of the sides of said body, cranks connecting said crank shaft and said plate, and means for rotating said crank shaft to carry said cranks in a forward direction 100 as they pass beneath the crank shaft.
3. In a manure spreader, the combination with a body, a rotatable beater at the rear of said body and a movable bottom for moving the load toward said beater, of a rotatable crank shaft journalized above the plane of the beater, a toothed plate pivotally supported on the cranks of said crank shaft, means for restraining the rotative movement of said plate about its pivotal connection, and means operative during the rotation of the beater for rotating said crank shaft.
4. In a manure spreader, the combination with a body, a rotatable beater at the rear of said body and a movable bottom for moving the load toward said beater, of a crank shaft journalized above the plane of the beater, a toothed plate pivotally supported on the cranks of said crank shaft, 110 a link connecting said plate with a fixed point to prevent its rotation about its pivotal support, and means for rotating said crank shaft.
5. In a manure spreader, the combination with a beater and means for moving the load toward said beater, of pivoted means for engaging the load above the plane of the beater, means for moving the pivot of said engaging means in a circular path, 120 125 130

and means for constraining said engaging means to move in a substantially elliptical path, having its major axis horizontal.

6. In a manure spreader, the combination
5 with a beater and means for moving the load toward said beater, of a pivoted arm adapted to engage a portion of the load above and beyond the influence of said beater, means for moving the pivot of said
10 arm in a circular path, and means for con-

straining the free end of said arm to move in horizontally disposed arcuate paths below the plane of said point.

Dated this twenty second day of January 1910.

THEOPHILUS BROWN.

PENELOPE COMBERBACH,
NELLIE WHALEN.

It is hereby certified that in Letters Patent No. 1,126,698, granted February 2, 1915, upon the application of Theophilus Brown, of Worcester, Massachusetts, for an improvement in "Manure-Spreaders," an error appears in the printed specification requiring correction as follows: Page 3, line 13, for the word "point" read *pivot*; and that the said Letters Patent should be read with this correction therein that the same may conform to the record of the case in the Patent Office.

Signed and sealed this 16th day of March, A. D., 1915.

[SEAL.]

J. T. NEWTON,

Acting Commissioner of Patents.
